UNITED STATES PATENT OFFICE.

MICHAEL SORG, OF INDIANAPOLIS, INDIANA.

SASH-CORD DEVICE.

1,352,846.

Specification of Letters Patent. Patented Sept. 14, 1920.

Application filed January 29, 1920. Serial No. 354,836.

To all whom it may concern:

Be it known that I, MICHAEL SORG, a citizen of the United States, residing at Indianapolis, in the county of Marion and State 5 of Indiana, have invented certain new and useful Improvements in Sash-Cord Devices, of which the following is a specification.

This invention relates to means for holding sash cords in place, more especially to 10 means for fastening the cords to a sash so as to render access thereto easy, particularly when it is desired to replace a broken cord. It is among the objects of this invention to produce a device of this character which is 15 extremely simple, reliable, easily accessible, does not mar the appearance of the sash, and will allow the ready replacement of a cord without removing the sash from the window casing.

20 In carrying the objects of my invention into effect, I provide a slot in the edge of the sash and an angularly disposed passage way leading into the body of the sash where a comparatively large opening is formed, 25 preferably circular. The opening has inserted therein a lining member having an opening registering with the angularly disposed passage and a cover member is provided which is simple to adjust and lies 30 flush with the surface of the window sash.

Referring to the accompanying drawings forming a part hereof and in which similar reference characters denote similar parts,

Figure 1, illustrates an elevation of a window with my invention in place,

Fig. 2, a detail of my device, some parts being shown in section for clearness,

Fig. 3, an enlarged view of the lining member, and

Fig. 4, shows the cover member in place.

The ordinary window sashes 1 and 2 are carried by the window casing 3 and have cords 4 running over pulleys 5 and attached thereto, the other end of the cords being 45 secured to weight members 6 within the window casing. In the upper portions of each of the sashes is formed a slot 8, the end of which connects by an angularly disposed passage 9 to a circular opening 10 to allow 50 the end 7 of the cord 4 to be fixed to the sash.

A lining member 11 having an opening

12 which registers with the passage 9 is inserted into opening 10. Ears 13 are provided and screws 14 inserted in the same 55 hold the lining member to the sash. Along the outer edge of member 11 is a recess 15 for the reception of a cover member 16 having one or more recesses 17 to enable the same to be removed with the aid of the 60 fingers. On the inner sides of cover 16 are placed spring fingers 18 having offset portions 19 which clamp the cover to the lining member.

When it is necessary to replace a cord, 65 due to the breaking of the one previously in place, the cover member 16 is removed, the end of the old cord taken out and a new cord fitted to the weight 6 and threaded over pulley 5. The free end thereof is then inserted in slot 8 and pushed down through angular passage 9 into opening 10 where it is tied in a knot. The cover member is then 70 replaced.

Having thus fully described my said invention, what I claim as new and desire to 75 secure by Letters Patent, is:

1. A sash cord device comprising a window sash, a slot on the edge thereof, an angularly disposed passage leading from said slot into the body of said sash, an opening in said sash, said angularly disposed passage communicating therewith, a cylindrical lining member secured in said opening, an opening in the periphery of said member 80 registering with said passage, means for securing said lining member on said sash, and means for covering the same, comprising a recess in said lining member, a cover plate fitting therein, spring members secured to 85 said cover plate, said spring members being adapted to engage said lining member to hold the cover plate in position, and means thereon to facilitate removal.

2. A sash cord device comprising a window sash, a slot on the edge thereof, an angularly disposed passage leading from said slot into the body of said sash, an opening in said sash, said angularly disposed passage communicating therewith, a lining 100 member secured in said opening, an opening in said member registering with said passage, means for securing said lining on said sash, and means for covering the same

comprising a recess in said lining member, a cover plate fitting therein, spring members secured to said cover plate, said spring members being adapted to engage said lining member to hold the cover plate in position, and means thereon to facilitate removal, the surfaces of said lining member and cover plate being flush with the surface of said window sash.

In witness whereof, I have hereunto set my hand and seal at Indianapolis, Indiana, this 23rd day of January, A. D. nineteen hundred and twenty.

MICHAEL SORG. [L. s.]
